UNITED STATES PATENT OFFICE.

WILLIAM CHURCHILL, OF CORNING, NEW YORK, ASSIGNOR TO CORNING GLASS
WORKS, A CORPORATION OF NEW YORK.

DESIGN FOR A TRANSPARENT COOKING-DISH.

55,366.

Specification for Design.

Patented June 1, 1920.

Application filed September 8, 1915. Serial No. 49,635. Term of patent 14 years.

To all whom it may concern:

Be it known that I, WILLIAM CHURCHILL, a citizen of the United States, residing at Corning, in the county of Steuben and State of New York, have invented a new, original, and ornamental Design for a Transparent Cooking-Dish, of which the following is a specification, reference being had to the accompanying drawing, forming part thereof.

In the drawing, Figure 1 is a perspective view of a cooking dish showing my design, and Fig. 2 is a plan view thereof.

The dish is made of transparent glass whereby not only can the observer see parts presented to him but whereby he can see through the walls of such parts other parts located therebehind.

I claim:

The ornamental design for a transparent cooking dish, as shown.

WILLIAM CHURCHILL.
